UNITED STATES PATENT OFFICE

THOMAS J. BUSH, OF LEXINGTON, KENTUCKY.

BRIDGE-PLATE FOR RAILWAY-JOINTS, &c.

SPECIFICATION forming part of Letters Patent No. 366,815, dated July 19, 1887.

Application filed July 9, 1886. Serial No. 207,608. (No model.)

To all whom it may concern:

Be it known that I, THOMAS J. BUSH, of Lexington, in the county of Fayette and State of Kentucky, have invented a new and Improved 5 Bridge-Plate for Railway-Joints, &c., of which the following is a full, clear, and exact description.

Reference is to be had to the accompanying drawings, forming a part of this specification, 10 in which similar letters of reference indicate corresponding parts in all the figures.

Figure 1 is a side elevation of a railway-joint formed with my new bridge-plate. Fig. 2 is a transverse sectional elevation of the same on the 15 line xx of Fig. 1, and Fig. 3 is an enlarged plan view of the lower surface of the bridge-plate.

The invention will first be described in connection with the drawings, and then pointed out in the claims.

20 The bridge-plate A is formed of a single plate of metal strengthened with the central curved side flanges, a , swaged from the edges of the plate in such manner that the flanges have a "truss" action and strengthen the plate 25 at its center, and also at the angles $a'a'$. The flat portions b of the bridge-plate, in forming a railway-joint, are adapted to rest upon the cross-ties B, where the plate is secured by spikes or bolts C C, passed through the orifices cc in 30 the plate and into the cross-ties. In the form of joint shown in the drawings the bolts C are bent interlocking bolts, inserted in diagonal intersecting holes bored in the cross-ties and provided with nuts d at their outer ends, which 35 screw down upon clamp-plates D D, which rest upon the flat portions b of the bridge-plate and the flanges of the rails E E; so the clamp plates and bolts secure the rails and bridge-plate firmly to the cross-ties. Between the

clamp-plates D D are secured to the webs of 40 the rails E the fish-plates F, the ends of which are contiguous to the said clamp-plates, so that they prevent the rails from "creeping" to any material extent. To prevent the clamp-plates D from displacement, and to facilitate 45 the putting of them down, I form the bridge-plate A with the upwardly-projecting lips e , against which the outer edges of the clamps rest, as shown clearly in Fig. 2.

By swaging the flanges a downward from 50 the body of the bridge-plate, and with lateral curvature, they form an elastic truss—that is to say, the plate being supported at its ends and loaded at the center, the tension along the lower or edge curve of the flanges causes said 55 lateral curvature to tend more or less to straighten, or, on the other hand, to take more curve, (the strain being reversed,) the result being an elastic truss calculated to adapt itself to the wave of deflection as said wave passes 60 through the joint of the track.

Having thus described my invention, what I claim as new, and desire to secure by Letters Patent, is—

1. The bridge-plate A, formed with the 65 curved strengthening-flanges a and flat surfaces b , in combination with the clamp-plates D D and interlocking bolts C C, substantially as described.

2. The plate A, formed with the curved 70 strengthening-flanges a and upwardly-projecting lips e , substantially as and for the purposes set forth.

THOMAS J. BUSH.
